DESIGN.

—o—

P. GROEGER.

WALL AND CEILING COVERING.

No. 19,624.

Patented Jan. 28, 1890.

UNITED STATES PATENT OFFICE.

PAUL GROEBER, OF RUTHERFORD PARK, NEW JERSEY, ASSIGNOR TO
FREDERICK BECK, OF NEW YORK, N. Y.

DESIGN FOR A WALL AND CEILING COVERING.

SPECIFICATION forming part of Design No. 19,624, dated January 28, 1890.

Application filed December 26, 1889. Serial No. 335,057. Term of patent 3½ years.

To all whom it may concern:

Be it known that I, PAUL GROEBER, a citizen of the United States, residing at Rutherford Park, in the county of Bergen and State of New Jersey, have invented and produced a new and original design for a Wall and Ceiling Covering, of which the following is a specification, reference being had to the accompanying drawing, forming part thereof.

5 The leading feature of my design consists of a Romanesque border, in which the convolutions of bands form H-shaped patterns 1, the termination of bands ending with scrolls 2. Single buttons with surrounding rays 3

10 and other buttons of different sizes in series,

15

4, are placed in spaces formed by the convolutions of bands. Perpendicular bands 5 and horizontal bands 6 form the upper and lower borders.

What I claim is—

20 The design for a wall and ceiling covering herein shown and described, consisting of convolutions of bands with terminating scrolls and ornamentation with buttons, with an upper and lower border of perpendicular and 25 horizontal bands.

PAUL GROEBER.
